(57) **CLAIM**

The ornamental design for a dual sensor hands-free sensor faucet, as shown and described.

DESCRIPTION

FIG. 1 is an upper left perspective view of the dual sensor hands-free sensor faucet.

FIG. 2 is a bottom-right perspective view of the dual sensor hands-free sensor faucet.

FIG. 3 is a rear view of the dual sensor hands-free sensor faucet.

FIG. 4 is a front view of the dual sensor hands-free sensor faucet.

FIG. 5 is a left side view of the dual sensor hands-free sensor faucet.

FIG. 6 is a right side view of the dual sensor hands-free sensor faucet.

FIG. 7 is a top view of the dual sensor hands-free sensor faucet; and,

FIG. 8 is a bottom view of the dual sensor hands-free sensor faucet.
